UNITED STATES PATENT OFFICE.

WILLIAM EDWARD HURRELL, OF LONDON, ENGLAND, ASSIGNOR TO PARKER H. SERCOMBE, OF MILWAUKEE, WISCONSIN.

VELOCIPED.

SPECIFICATION forming part of Letters Patent No. 448,580, dated March 17, 1891.

Application filed September 1, 1890. Serial No. 363,623. (No model.)

To all whom it may concern:

Be it known that I, WILLIAM EDWARD HURRELL, a subject of the Queen of Great Britain, residing at London, in the county of Middlesex, England, have invented certain new and useful Improvements in Velocipedes, of which the following is a full and clear description.

My invention relates to an improved spring-fork for the steering-wheel of a velocipede, and to an improved brake for use therewith, the object being to reduce vibration arising from the steering-wheel, and to so compensate the brake-spoon lever that its action is not impaired by the "jigging" motion of the wheel relative to the main fork of the frame carrying it. I attain this end in the manner illustrated by the accompanying drawings, in which—

20 Figure 1 is a broken view in side elevation showing my improved spring-fork and compensated brake. Fig. 2 is a perspective view of the spring-fork detached, and Fig. 3 is a perspective view of the brake-spoon lever detached.

Throughout these views similar parts are marked with the same letters of reference.

Onto the end of each prong of the main fork A, adapted to carry the steering-wheel, 30 B, is fulcrated a rocking lever C. The forward ends of these levers are adapted to carry the axle b of the steering-wheel.

To the rear ends of the levers C C is jointed a supplemental fork D, the prongs of which 35 terminate in a crown d, from which extends a central stem d', adapted to slide through an eye in a bracket a', formed on or fixed to the crown A' of the main fork.

On the stem d' is placed a coiled or spiral 40 spring E, acting between the bracket a' and a nut and washer d² on the free end of the said stem. It will thus be seen that when the steering-wheel meets an obstacle on the road it is allowed to rise, due to the rocking 45 action of the levers C C, controlled by the spring E, through the supplemental fork D.

The brake-spoon lever F, instead of being fulcrated to the crown A' of the main fork, is bifurcated at its rear end and fulcrated to 50 the prongs at the crown d of the supplemental fork D, and the point of connection

of the operating rod or plunger F' is at such a position on the spoon-lever F as will give it an equivalent movement to that of the rocking levers C C, so that the brake-spoon 55 is automatically compensated to the movement of the steering-wheel, and always remains at one uniform distance from the periphery thereof, whether the brake is on or off. It will thus be seen that the jigging motion of the wheel is not transmitted to the operating-rod or plunger F'.

I wish it to be particularly understood that I do not limit myself to the precise details of construction herein described and shown, 65 but hold myself at liberty to make such changes and alterations as fairly fall within the spirit and scope of my invention.

Having now particularly described my invention and in what manner the same is carried to practical effect, what I claim is—

1. In a velocipede, the combination of a main fork having a rearwardly-extended bracket, levers fulcrated to the ends of the fork-prongs, an axle supported by the forward ends of the levers, a wheel carried on the axle, a supplemental fork connected to the rear ends of said levers and provided with a spring-controlled stem loosely engaging the rearwardly-extended bracket on said main fork, and a lever-controlled brake-spoon fulcrated to the supplemental fork, substantially as set forth.

2. In a velocipede, the combination of a main fork having a rearwardly-extended bracket, levers fulcrated to the ends of the fork-prongs, an axle supported by the forward ends of the levers, a wheel carried on the axle, a supplemental fork connected to the rear ends of said levers and provided with a spring-controlled stem loosely engaging the rearwardly-extended bracket on said main fork, and a lever-controlled brake-spoon having a bifurcated rear end fulcrated to the prongs of said supplemental fork, substantially as set forth.

In witness whereof I have hereunto set my hand in presence of two witnesses.

WILLIAM EDWARD HURRELL.
